CLAIM

The ornamental design for a mobile phone, as shown and described.

DESCRIPTION

FIG. 1 is a front perspective view of a mobile phone showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dot-dash broken lines in the figures, and the evenly spaced dashed broken lines in the figures that are immediately adjacent to the shaded areas and define unshaded regions, represent the bounds of the claimed design. All other broken lines, including the features within broken line boundaries, are directed to environment. The broken lines form no part of the claimed design.
